UNITED STATES PATENT OFFICE.

DAVID H. STICKNEY, OF CINCINNATI, OHIO.

COCK.

Specification of Letters Patent No. 25,853, dated October 18, 1859.

To all whom it may concern:

Be it known that I, DAVID H. STICKNEY, of Cincinnati, Hamilton county, State of Ohio, have invented a new and Improved 5 Cock or Faucet; and I hereby declare the following to be a full, clear, and exact description of the same, reference being had to the accompanying drawings, making part of this specification.

10 The present improvement refers to the class of cocks or faucets which open by simply depressing a hollow piston and which close by the interior pressure; and the invention consists chiefly in a provision for the 15 effective lubrication of the packing around the piston by means of the discharging fluid itself.

15 In the accompanying drawings, Figure 1 is a side elevation. Figs. 2 and 3 are axial 20 sections giving the closed and open positions respectively. Fig. 4 is an axial section exhibiting the invention as applied to a gage cock for steam boilers.

25 The cap B which closes the stuffing box C of the barrel A is prolonged upward so as to form around the piston E an annular space or chamber D whose length slightly exceeds the desired range of said piston. The space D may be closed at top by a suitable 30 screw cap F.

35 The piston E consists of a cylindrical tube closed at its ends and provided at top with a knob J adapted for pressure of the hand, at or near its upper end with a discharge 40 nozzle H, near its lower end with inlets G, and at about its mid-length with a collar I, which limits the play of the piston and in 45 applications where it is needful may be adapted to form a tight joint in connection with the inner surface of the cap F, when 50 the piston is in its outer position.

55 The act of opening the cock, consists simply in pressing in the piston as in Fig. 3, the fluid entering from the barrel A in opposite 60 and equal streams which balance each other so as to avoid any side pressure or wear. On the withdrawal of the hand the pressure of 65 fluid within restores the piston to its outer position so as to remove the inlets G from 70 the supply, and to bring them into communication with the chamber D which is thus 75 kept constantly charged with moisture. A body of fluid being thus provided outside, as 80 well as within the stuffing box C the packing

is kept constantly moist and watertight, and 55 the piston constantly lubricated.

85 In Fig. 4 the invention is represented as applied to a gage cock for locomotive and other steam boilers. In this case the piston E is provided near its outer end with a simple aperture g, which in the act of pressing in the piston so as to open the cock is brought into juxtaposition with a nozzle H' which is fixed in the cap B. At this time the steam or water passing from the barrel A through the 60 aperture G is discharged downward through the apertures g and nozzle H'. Upon the piston returning to its outer position a portion of the fluid escapes through the apertures G into the chamber D and keeps the 65 packing in a moist and lubricated condition.

70 This cock is simple in its construction and is found to continue effective for a very long period, which is partially due to the fact that the surfaces of the passages are not depended upon to produce steam or water tight joints. The apertures are entirely isolated 75 from the packing except for an instant during the act of opening or closing the cock; by which means the softening and destruction 80 of the packing and the consequent choking of the passages are in a great measure avoided. A cock of this construction is also exempt from liability to open by the jar or shaking of machinery. At every motion of 85 the piston, lime or other sediment is wiped from its surface by the packing. By the use 90 of a hollow piston whose perforations may be placed on either side of a stationary stuffing box in the manner explained, a single packing is adapted to perform functions which would otherwise require two:—one of which must be exposed to atmospheric influence.

95 I claim as new and of my invention and desire to secure by Letters Patent—

The supplementary chamber D and stationary stuffing box C, in combination with a hollow piston E having ingress apertures G, adapted to be placed on either side of the 100 said stuffing box by the motion of the piston as set forth.

In testimony of which invention, I hereunto set my hand.

D. H. STICKNEY.
